US0D1113884S

(12) **United States Design Patent** (10) **Patent No.:** **US D1,113,884 S**
(45) **Date of Patent:** **** Feb. 17, 2026**

(54) **ANTENNA**

(71) Applicant: **Japan Aviation Electronics Industry, Limited**, Tokyo (JP)

(72) Inventor: **Jun Uchida**, Tokyo (JP)

(73) Assignee: **Japan Aviation Electronics Industry, Limited**, Tokyo (JP)

(**) Term: **15 Years**

(21) Appl. No.: **29/958,441**

(22) Filed: **Aug. 20, 2024**

(30) **Foreign Application Priority Data**

Mar. 5, 2024 (JP) ..... 2024-004543 D

(51) **LOC (15) Cl.** **14-03**

(52) **U.S. Cl.**

USPC **D14/230**

(58) **Field of Classification Search**

USPC D14/230, 231-140, 238.1, 299, 343, 289, D14/492, 138, 258; D13/182; D12/42-43

CPC H01Q 9/285; H01Q 19/30; H01Q 19/12; H01Q 1/36; H01Q 1/38; H05K 11/00; G05D 1/0234; G06K 19/07749; G01R 29/10; G01S 2013/0245; G01S 1031/0254; G01S 2013/0263; G01S 7/4026; H04B 1/0475; H04B 1/034

(57) **CLAIM**

The ornamental design for an antenna as shown and described.

DESCRIPTION

FIG. 1 is a front elevational view of an antenna showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front, top, and right side perspective view thereof;

FIG. 8 is a rear, bottom, and left side perspective view thereof;

FIG. 9 is a front, right, and bottom side perspective view thereof; and,

FIG. 10 is a rear, left, and top side perspective view thereof.

1 Claim, 7 Drawing Sheets
